Primary Examiner — Ania Aman(74) *Attorney, Agent, or Firm* — CANTOR COLBURN LLP(57) **CLAIM**

The ornamental design for a heater, as shown and described.

DESCRIPTION

FIG. 1 is an upper perspective view of a heater, showing our new design;

FIG. 2 is a lower perspective view of the heater shown in FIG. 1;

FIG. 3 is a side view of the heater shown in FIG. 1, the opposite side being a mirror image thereof;

FIG. 4 is a front view of the heater shown in FIG. 1, the rear view being a mirror image thereof;

FIG. 5 is a top view of the heater shown in FIG. 1; and,

FIG. 6 is bottom view of the heater shown in FIG. 1. The broken lines in the figures depict environmental subject matter and form no part of the claimed design.

1 Claim, 6 Drawing Sheets(56)
